UNITED STATES PATENT OFFICE.

LOUIS B. HASBROUCK, OF ELMIRA, NEW YORK, ASSIGNOR TO ECLIPSE TEXTILE DEVICES, INC., OF ELMIRA, NEW YORK, A CORPORATION OF NEW YORK.

METHOD AND APPARATUS FOR CLEANING YARN.

Application filed April 23, 1926. Serial No. 104,010.

This invention relates to a method and apparatus for cleaning yarn, and aims to remove impurities, such as parts of seeds, parts of stems, slubs, specks, and other particles from yarn before the yarn is formed into fabric, so that a superior quality of fabric may be produced from comparatively inexpensive yarns.

An important feature of the invention 10 consists in using a travelling yarn to clean a cleaner, by means of which the yarn has been cleaned. The new method of yarn cleaning incorporating this feature consists in (1) applying a scraper, comb, or other 15 cleaning means to a travelling yarn in such relation thereto as to remove particles and some fibrous matter from the yarn, (2) so changing the relation of the cleaning means to the travelling yarn that the particles and fibrous matter remaining in the cleaning 20 means become loosely reattached to the yarn and are thus drawn away from the cleaning means, and (3) removing from the travelling 25 yarn, at a further point in its travel, the particles and fibrous matter which have been loosely reattached to it.

The new method may be carried out manually by applying the scraper or comb to the 30 yarn in a forwardly inclined position to clean the yarn, and then turning the scraper or comb so that the yarn draws from it the particles and fibrous matter which it has removed from the yarn. The loosely reattached matter may easily be removed from 35 the yarn at a further point in its travel by the fingers or by means of an ordinary slub catcher.

An important part of the invention 40 consists in providing an automatic self-cleaning yarn cleaner for carrying out the new method. This and other features of the invention may best be understood by a detailed 45 description of a specific device embodying the apparatus features of the invention and adapted to carry out the method feature of the invention. Such a device is shown in the accompanying drawings in which:—

Fig. 1 is a side elevation of a cleaning 50 unit and means for supporting and operating it, sectioned on the line 1—1 of Fig. 2;

Fig. 2 is a plan view of the cleaning unit 55 and associated parts shown in Fig. 1;

Fig. 3 is an enlarged side elevation of 60 the cleaning unit, sectioned on the line 3—3 of Fig. 4;

Fig. 4 is a front elevation of the cleaning unit, sectioned on the line 4—4 of Fig. 3; Fig. 5 is an enlarged section on the line 5—5 of Fig. 3, showing the deflector; and Fig. 6 is an enlarged prospective view of 65 one of the blades, showing the wheel sectioned on the lines 6—6 of Figs. 3 and 4.

The cleaning unit 10 shown in the drawings, may be one of a number of such units mounted along the front of a winding, spooling or other machine into which yarn is drawn. One such unit may be provided for each thread drawn into the machine. The units may conveniently be supported on a frame, consisting of end pieces 11 projecting outwardly from the frame of the winding or other machine, and two rods 12, 13 extending between the end frames. The rod 12 is fixed with end pieces. The rod 13 is 70 really a shaft and is journalled for rotation in each of the end pieces. The shaft 13 is slowly rotated in a clockwise direction (Figs. 1 and 3) by any convenient means. It is usually desirable to cause such rotation by connecting the shaft 13 with a moving part of the mechanism of the winding or other machine on which the cleaning apparatus is mounted. In the arrangement shown in Figs. 1 and 2, a rocking shaft A 75 of the winding machine bears an arm 14 connected by a rod 15 to a disk 16 loosely mounted on the shaft 13. The disk 16 carries a spring pressed pawl 17 which causes a slow step-by-step rotation of the shaft 13 by engagement with a ratchet 18 fixed on 80 the shaft. It is not essential that the shaft 13 have a step-by-step movement, but the arrangement shown affords a simple and convenient method of giving this shaft the slow rotation required for operating the cleaning 85 units as hereinafter explained.

The cleaning unit 10, comprises a wheel 19, mounted on the rotary shaft 13, and non-rotary parts—including thread guides 20, 21, a guard 22, and a deflector 23—supported by an arm 24 adjustably secured to the fixed rod 12. An additional thread guide 25 and a tension device 26 of usual construction may be mounted on the arm 24 90 in front of the thread guide 20.

The primary cleaning elements of the device are a set of blades or teeth 31, projecting outwardly from the rim 32 of the wheel 19. In describing the blades, I shall designate as the front surface of each blade 110

that surface which, when the blade is operating upon the yarn, faces in the direction from which the yarn is travelling. Each blade 31 has a front surface 33, which makes 5 an acute angle with the rim 32, and a semi-cylindrical grooved end surface 34, parallel to the rim 32, and intersecting the front surface 33 to form an acute in-curved semi-circular scraping edge 35. The radius of 10 the edge 35 is substantially equal to that of the yarn to be cleaned, so that the edge surrounds one half the circumference of a yarn which is drawn across it. A pair of guiding and deflecting ears 36 project from the 15 outer end of each blade. The front surfaces 37 of each of these ears are a continuation of the front surface 33 of the blade, while the opposite inner surfaces 38 of the ears diverge from the grooved outer end 20 surface 34 of the blade, to provide a guiding slot 39.

The wheel 19 has side flanges 40, 40', which cooperate with its rim 32 and the 25 blades 31 in providing pockets 41 between the blades. To facilitate machining and finishing the blades, the wheel 19 is made in two parts. One part includes a hub 42 and a disk 43, the outer portion of which forms the side flange 40. The blades 31 are formed integral with this part of the 30 wheel. The second part of the wheel has the form of an angle ring and provides the cylindrical rim 32 and the side flange 40', which fit closely against the inner ends 35 and outer side edges of the blades 31 respectively.

The thread guides 20 and 21, are positioned on opposite sides of the wheel 19, so that a yarn drawn under the thread guide 40 20, and over the thread guide 21, is brought in contact with the cleaning edges 35 of several of the blades 31 of the wheel 19 for example, with the cleaning edges of the four blades marked 31^a in Fig. 3.

45 On the guard 22, which covers the rear side of the wheel 19 and contains a slot 45 for the passage of the yarn, is mounted the deflector 23, which comprises two blades 46, 46' inclined to the direction of the travel 50 of the yarn as it passes from the blades 31^a to the thread guide 21. The inner edges 47, of the blades 46, 46', are parallel and are spaced apart by a distance substantially equal to the diameter of the yarn which 55 is being cleaned. In order to adapt the device for operation on yarns of different sizes, means are provided for adjusting the distance between the edges 47. For this purpose, the blade 46' is slidably mounted. 60 This blade has flanges 48 slidably engaging the side faces 49 of a projection 50 on the guard 22, and contains a slot 51, embracing a screw 52, which is screwed into the projection 50. The blade is adjusted and held 65 in adjusted position by a tension screw 53

and a compression spring 54, which extend between a bracket 55, mounted on the projection 50, and an upstanding flange 56 at the back edge of the blade. The screw has a threaded engagement with the flange 56, 70 while its head is held against the bracket 55 by the spring 54.

The use and operation of the yarn cleaner described is as follows:—

The cleaner is threaded by passing the 75 yarn through the thread guide 25, the tension device 26, then under the thread guide 20, through the slot 45 in the guard 22, and between the blades 46, 46' of the deflector 23. This brings the yarn between 80 the deflecting ears 36 of the blades 31^a which guide it into contact with the scraping edges 35 of the blades.

The winding machine to which the yarn cleaner is attached is then started, drawing 85 the yarn forward and at the same time slowly rotating the shaft 13 and wheel 19. The peripheral speed of the wheel and its blades is much less than the speed of the 90 yarn. The tension applied to the yarn by the tension device 26 draws it into close contact with the curved scraping edges 35 of the blades 31^a, owing to the fact that the 95 yarn turns inward through a small angle as it crosses each scraping edge. The twist 100 of the yarn and the fact that it is thus drawn closely against the scraping edges cause the yarn to rotate as it crosses the scraping edges, so that each part of the circumference of the yarn is brought against one or another of these semi-circular edges. As the yarn travels across the scraping edges, 105 these edges remove from the yarn all specks and other impurities which adhere to the 110 yarn or are embedded therein. The particles removed from the yarn together with some fibrous matter which necessarily adhered to them, are directed by the inclined front surfaces 33 of the blades and the front surfaces 37 of the ears 36, into the 115 pockets 41^a, in front of the scraping edges with which the yarn is in contact.

As the pockets are closed except at their 120 tops, the particles and fibrous matter are confined therein. The fibrous matter in each 125 pocket constantly tends to become re-entwined with the yarn crossing the top of the pocket and is constantly scraped free from the yarn at the scraping edge 35 at the rear corner of the pocket. It follows that the yarn crossing the top of each pocket causes a rotation of the fibrous matter contained therein which forms the fibrous matter into a more or less compact bunch or ball, containing all the particles which have been removed from the 130 yarn by the scraping edge behind the pocket.

As the wheel 19 slowly rotates, each blade 135 whose scraping edge has been operating upon the yarn is drawn out of contact with

the yarn (see blade 31^b in Fig. 3). When this occurs, the fibrous matter in the pocket 41^b in front of this blade, which has constantly tended to become re-entwined with the yarn, is no longer scraped from the yarn. As a result, the entire bunch of fibrous matter and particles is pulled out of the pocket by the yarn and travels off with the yarn. This leaves the pocket and the blade behind 10 it clean and ready to operate on the yarn again when the rotation of the wheel shall have brought its scraping edge again into contact with the yarn.

The bunches of fibrous matter and particles, which have become loosely reattached to the yarn, strike the blades 46, 46' of the deflector 23, and are thereby freed from the 15 yarn and deflected downward just outside the guard 22. This guard prevents them from striking the wheel 19. Consequently, they fall below the cleaner and may be collected in any convenient suitable receptacle.

It is apparent from the above description that the device described carries out automatically the new method of cleaning which was described at the beginning of this specification. The method of the invention is however by no means limited to any specific mechanism for carrying it into effect, nor are the apparatus features of the invention limited to the specific device described, except in so far as specified in the claims which follow:

What I claim is:

1. The method of cleaning yarn, which comprises applying cleaning means to a travelling yarn in such relation thereto as to remove particles and some fibrous matter from the yarn, so changing the relation of the cleaning means to the travelling yarn that the yarn draws from the cleaning means the fibrous matter and particles collected therein, and removing such fibrous matter and particles from the yarn at a further 45 point in its travel.

2. The method of cleaning yarn, which comprises removing particles and fibrous matter from a travelling yarn at one point of its travel, loosely reattaching the matter removed to the yarn at a further point in its travel, and removing the reattached matter from the yarn at a still further point in its travel.

3. The method of cleaning yarn, which comprises scraping particles and fibrous matter from a travelling yarn at one point of its travel and collecting the matter removed, loosely reattaching the collected matter to the yarn at a further point in its travel, and removing the reattached matter from the yarn at a still further point in its travel.

4. A yarn cleaner comprising means providing a scraping edge and a pocket in front

of said scraping edge, means for guiding a 65 travelling yarn across the top of said pocket and transversely across said scraping edge, and means for causing a separating movement between the scraping edge and the yarn to permit the yarn to withdraw from 70 the pocket the fibrous matter and particles collected therein.

5. In a yarn cleaner, means providing a pocket having a scraping edge at the top of its back wall, means for positioning the 75 scraping edge in contact with a travelling yarn with the back wall of a pocket inclined toward the direction from which the yarn is travelling, and means for removing the scraping edge from the yarn and tipping 80 the back wall of a pocket rearwardly from its first position.

6. In a yarn cleaner, means providing a pocket having a scraping edge at the top of its back wall, means for positioning the 85 scraping edge in contact with a travelling yarn with the back wall of a pocket inclined toward the direction from which the yarn is travelling, and means for tipping the back wall of a pocket rearwardly from its first 90 position.

7. A yarn cleaner, comprising a series of scraping blades, means providing a pocket in front of each blade, means for guiding a travelling yarn across the top of said 95 pockets and transversely across the blades, means for successively withdrawing said blades from contact with the yarn, and a deflector embracing the yarn beyond said blades.

8. A yarn cleaner, comprising a series of scraping blades, means providing a pocket in front of each blade, means for bringing each blade successively into and out of contact with a travelling yarn so that particles 105 of fibrous matter are scraped from the yarn by each blade and then withdrawn from its pocket by the yarn, and means for removing from the yarn the particles of fibrous matter withdrawn from the pockets.

9. In a yarn cleaner, a wheel, a plurality of scraping blades projecting from the periphery of said wheel, side flanges on the wheel cooperating with said blades to provide pockets between them, means for guiding a travelling yarn across the top of said 110 pockets and across the edges of said blades on a part of the circumference of the wheel, means for rotating the wheel to cause its blades to move in the same direction as the 120 travelling yarn but at less speed.

10. In a yarn cleaner for operating on a travelling yarn, the combination of means forming a pocket having its upper rear edge in contact with the yarn and its back 125 wall inclined toward the direction from which the yarn is travelling, and means for changing the relation of the pocket to the

- 4
1. In a yarn cleaner, a rotary wheel, a series of blades on the periphery of the wheel inclined rearwardly with respect to its direction of rotation, side flanges cooperating with said blades to form pockets between them, and means for guiding a travelling yarn across the top of said pocket and blades in the direction of movement of the blades and at a greater speed.
2. In a yarn cleaner comprising a pair of blades located one behind the other, and having scraping edges at the middles of their outer ends, ears projecting from the outer ends of each blade at opposite sides of its scraping edge, and side walls joining said blades and ears to provide a pocket between them.
3. In a yarn cleaner for operating on a travelling yarn, a blade having a scraping edge at the middle of its outer edge and diverging ears projecting from its outer end at opposite sides of its scraping edge, means providing a pocket in front of said blade, and means for positioning said blade with its front surface inclined toward the direction from which the yarn is travelling.
4. In a yarn cleaner comprising a rotary wheel, blades projecting from the periphery of the wheel, each having a scraping edge at the middle of its outer end, diverging ears projecting from the outer end of each blade at opposite sides of its scraping edge, and side flanges cooperating with said blades and ears to form pockets between them.
5. In a yarn cleaner, a wheel, a plurality of scraping blades projecting from the periphery of said wheel and each having at its outer end an incurved acute scraping edge, side flanges on the wheel cooperating with the blades to provide pockets between them, thread guides at opposite sides of the wheel for guiding a travelling yarn across the top of said pockets and across the scraping edges of said blades on a part of the circumference of the wheel, means for placing the travelling yarn under tension so that it is drawn into close contact with said scraping edges, and means for rotating the wheel to cause its blades to move in the same direction as the travelling yarn but at less speed.
6. In a yarn cleaner, a series of blades having their ends positioned on a convex curve and each having a concave scraping edge at its end, means for guiding a travelling yarn across the scraping edges of said blades in succession, and means for placing the travelling yarn under tension so that it is drawn into close contact with said scraping edges.
7. In a yarn cleaner, a blade having a grooved end surface and a front surface meeting said end surface in an acute incurved scraping edge, thread guides guiding a travelling yarn across said edge and along the groove in the end surface and positioned to cause the yarn to bend inward in crossing said edge, and means for placing the travelling yarn under tension so that it is drawn into firm contact with said edge.
8. In a yarn cleaner, a blade having a semi-circular concave scraping edge, thread guides directing a travelling yarn across said edge and positioned to cause the yarn to bend inward as it crosses the edge, and means for placing the travelling yarn under tension so that it is drawn into close contact with said edge.
9. In a yarn cleaner, a wheel, blades projecting from the periphery of said wheel and each having a scraping edge at its outer end, a guard over said wheel containing a slot, means for guiding the yarn passed into said slot into contact with the scraping edges of the blades.
10. In a yarn cleaner, the combination with a device cooperating with a travelling yarn to remove, collect and loosely re-attach particles and fibrous matter, of a pair of blades transverse to the yarn and having opposed spaced edges embracing the yarn beyond said device to remove such re-attached matter therefrom, and a guard to deflect the matter removed by the blades away from said device.
11. A yarn cleaner, comprising a rotary wheel having peripheral blades with pockets between them, a guard partially surrounding said wheel, a pair of fixed blades having spaced inner edges mounted on said guard, and means for guiding a travelling yarn across the ends of the blades at the upper part of the wheel and then between said fixed blades.
12. In a yarn cleaner, a wheel comprising a disk, blades integral with said disk projecting from one side thereof and arranged in a circle, and an angle ring having a cylindrical flange fitting against the inner ends of the blades and a flat flange fitting against the outer side edges of the blades.
- In testimony whereof I have hereunto set my hand.
- LOUIS B. HASBROUCK.
